THOMAS A. HUNTER AND JOHN BLEWITT, OF NEW YORK, N. Y.

Letters Patent No. 92,053, dated June 29, 1869.

IMPROVEMENT IN LAMP-BRACKETS.

The Schedule referred to in these Letters Patent and making part of the same.

To all whom it may concern:

Be it known that we, THOMAS A. HUNTER and JOHN BLEWITT, of the city and State of New York, have invented and made a new and useful Improvement in Lamps; and we do hereby declare the following to be a full, clear, and exact description of the said invention, reference being had to the annexed drawing, making part of this specification, wherein—

Figure 1 is a side view of our lamp and its holder. Figure 2 is a sectional plan of the same below the line *x x*.

Figure 3 is a section of the base of the lamp-holder in a slightly modified form.

Similar marks of reference denote the same parts. We make use of a lamp with a fountain or reservoir, *a*, that rises higher than the burner-collar *b*, and introduce a cylinder, *c*, that is fitted tightly to place and receives the wick of the burner, the same as shown in our Letters Patent, granted November 3, 1868, No. 83,711.

Our present invention consists in projections or ribs running more or less around the reservoir, combined with clips by which the lamp is attached to a gas fixture, to the edge of a table, shelf, mantel, or other horizontal support, or may be connected to a vertical support, such as the edge of a door or blind, the mullions or sash-bars of a window, or other convenient place of attachment.

The projections or ribs *e* are upon the lower part of the reservoir *a*, and *ff* are the clips for receiving and supporting the reservoir. These clips may be made with three arms, two of which are hook-ended and the other provided with a screw or other means for clamping, and these clips may be adapted to setting upon the end of a gas-fixture, as seen at *g*, fig. 3.

We have shown, and prefer that the clips *ff* stand as arms from the vertical pivot *h*, that sets into a hole

in the socket *k*, so as to allow of the lamp being swung into any desired position horizontally.

The bracket, or socket *k*, is made as a three-sided clip, with a clamping-screw, *l*, and a second hole, as at *i*, passes through the projecting end of the bracket, so that the pivot *h* can be entered therein when the clip *k* is attached to the edge of a shelf or other horizontal article. In the drawing this clip *k* is shown as in a position for being attached to the edge of a blind or other vertical article.

Provision is made for the introduction of screws at *m*, so that the bracket can be sustained by them when its position is permanent, and the two holes for the pivot *h* allow said bracket to be attached either vertically or horizontally, as may be most convenient.

If the rib *e* was made upon the bottom of the reservoir, it might be shaped so that the hooks or means of attachment act outwardly from within said ring instead of from the outside.

What we claim, and desire to secure by Letters Patent, is—

1. The clips *f*, fitted to receive the lower part of the lamp-reservoir, in combination with the rib or projection upon said reservoir, as and for the purposes set forth.
2. The bracket, or socket *k*, formed with two holes at right angles to each other, for receiving the pivot *h*, and provided with the clamping-screw *l*, as and for the purposes set forth.

In witness whereof, we have hereunto set our signatures, this 17th day of April, A. D. 1869.

T. A. HUNTER.
JOHN BLEWITT.
